UNITED STATES PATENT OFFICE.

BURTON A. COOK, OF HOLLYWOOD, CALIFORNIA, ASSIGNOR TO COOK WOODCRAFT CO.,
OF HOLLYWOOD, CALIFORNIA, A COPARTNERSHIP.

DESIGN FOR A FLOWER BOX.

Application filed December 26, 1923. Serial No. 8,149. Term of patent 3½ years.

To all whom it may concern:

Be it known that I, BURTON A. Cook, a citizen of the United States, residing at Hollywood, in the county of Los Angeles and State of California, have invented a new, original, and ornamental Design for Flower Boxes, of which the following is a specification, reference being had to the accompanying drawing, forming a part thereof.

I claim:

The ornamental design for a flower box, as shown.

BURTON A. COOK.
